N. K. F. HANSON

MEANS FOR BOILING FIBROUS MATTERS

Filed March 11, 1926

Inventor,
Nils K. F. Hanson,
By *Henry Orth* atty.

UNITED STATES PATENT OFFICE.

NILS KNUT FREDRIK HANSON, OF STOCKHOLM, SWEDEN.

MEANS FOR BOILING FIBROUS MATTERS.

Application filed March 11, 1926, Serial No. 93,986, and in Sweden October 18, 1924.

This invention relates to the boiling of fibrous matters in order to extract the viscous substance from between the fibers, and more particularly to the digesting of sulphite pulp.

In the manufacture of sulphite cellulose the extraction of the incrusting substances is effected, as well known in the art, by digesting the pulp with an acid salt, as bisulphite, comprising sulphurous acid dissolved in water, said acid solution containing in turn a solution of monosulphite (as calcium sulphite, magnesium sulphite or the like). In such digesting process the free sulphurous acid active in the process of extracting the incrusting substances will be caused to withdraw from the digesting liquid to an extent depending on the temperature and the pressure inside the digester. The sulphurous acid thus released collects above the wood and liquid contained in the digester and does not, consequently, assist to the extraction of the incrusting substances.

The invention has for its object to cause said sulphurous acid to assist to the extraction of the incrusting substances whereby a considerable reducing of the duration of the digesting process is obtained.

With this object in view the gas produced as a result of the digesting process is removed from the upper portion of the digester and again introduced into the digester at the bottom thereof so as to be caused to pass upwardly through the digester. The gas is in this way caused to pass the whole height of wood and liquid contained within the digester and will during said passage engage the incrusting substances to assist to the extraction thereof from the wood.

By said circulation of the gas two further advantages are obtained, that is, on the one hand, an improved distribution of the temperature inside the digester and, on the other hand, an improved circulation of the liquid, which advantages result in a more uniform output.

It has already been proposed to improve the distribution of the temperature and the circulation of the liquid by circulation of the liquid itself, such circulation, however, will be inefficient as compared with our improved circulation of the gas and does not, moreover, render the free gas available for the extracting process.

In the accompanying drawing a plant

embodying the principles of this invention is shown diagrammatically.

Referring to the drawing, the numeral 1 represents any desired type of sulphite pulp digester. Extending from the top of the digester are two pipes 2 and 3 each connected at its other end to the top of a receptacle 4 and 5, respectively. Inserted in each of said pipes 2 and 3 is a back-pressure valve 6 and 7, respectively, adapted to open due to a suction in the respective receptacle and close upon an increase of the pressure therein. Extending from the top of each receptacle 4 and 5 to the bottom of the digester 1 is also a pipe 8 and 9, respectively. Also these pipes are provided with back-pressure valves 10 and 11, respectively, so designed as to open as a result of an increase of the pressure inside the respective receptacle and close due to a suction from the receptacle.

Extending from the lower portion of each receptacle 4 and 5 is a pipe 12 and 13, respectively, each of which divides into two branches connected to the inlet and outlet, respectively, of a centrifugal pump or the like 14. Each of the four pipe branches thus formed is provided with a valve 15, 16, 17, 18, respectively. Said valves are adapted to be controlled in such a way that one of the two valves associated with one and the same pair of branches is open and the other closed when the corresponding valves of the other pair of branches is, respectively, closed and open, thus enabling the pump to effect a transmission of liquid in either direction between the two receptacles.

The control of the valves is, preferably, effected automatically by means controlled by the liquid levels within the receptacles, as indicated at 19 and 20 in the drawing.

The operation of the plant is as follows:

Let it be assumed that one of the receptacles, as 4, is filled with liquid and the other substantially empty. By means of the pump 14 the liquid is passed from the receptacle 4 to the receptacle 5. As a result, gas is drawn out from the upper portion of the digester 1 through the pipe 2, while gas that may be contained in the receptacle 5 as a result of a preceding suction operation similar to that above described, will be caused to enter the lower portion of the digester through pipe 9 and pass upwardly through the digester while assisting to the extraction of the incrusting substances, as already men-

tioned. The receptacle 4 having been emptied of liquid and the receptacle 5 having been filled with this liquid the valves 15—18 are reversed so as to cause the liquid to be 5 returned from receptacle 5 to receptacle 4. As this return movement of the liquid proceeds gas is drawn into the receptacle 5 from the upper portion of the digester, while the gas previously drawn into the receptacle 4 is 10 caused to enter the digester at the bottom thereof through pipe 8.

By alternate filling and emptying the receptacles 4 and 5 in the way described a practically continuous gas transfer may be effected outside the digester from the upper to 15 the lower portion thereof.

If the reversing of the valves 15—18 be effected when either of the receptacles 4 or 5 is completely filled with liquid any clearance 20 is avoided and the gas current will be as continuous as possible.

It is to be noted that variations may be made without departing from the principle of the invention. Thus, for instance, a single receptacle may be used for effecting the 25 circulation of the gas. In such case, said receptacle is caused to alternately act by suction and pressure, while another receptacle is provided merely for the purpose of receiving 30 the liquid. If desired, the liquid may be

substituted by steam or gas under pressure in which case steam or gas valves are substituted for the valves 15—18.

What I claim is:

1. An apparatus for treating fibrous materials in order to extract viscous substances therefrom comprising a digester, two receptacles, a connection between said receptacles, a pump mechanism in said connection adapted to pass a fluid in either direction through 35 said connection, separate connections between each receptacle and the top and bottom of said digester, and back-pressure valves inserted in said last-mentioned connections. 40

2. An apparatus for treating fibrous materials in order to extract viscous substances therefrom comprising a digester, two receptacles adapted to be alternately filled with liquid, a connection between said receptacles, 45 a liquid pump mechanism in said connection, means controlled by the liquid lever in said receptacles to reverse the flow of liquid in said connection, separate connections between each of said receptacles and the top and bottom of the digester, and back-pressure valves in said last-mentioned connections. 50

In testimony whereof I have signed my name.

NILS KNUT FREDRIK HANSON.
